RAILWAY TRAFFIC CONTROLLING APPARATUS

Filed May 17, 1929

UNITED STATES PATENT OFFICE

CHARLES A. BROOKS, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY-TRAFFIC-CONTROLLING APPARATUS

Application filed May 17, 1929. Serial No. 363,817.

My invention relates to railway traffic controlling apparatus, and has for an object the provision of novel and improved means for the control of traffic over stretches of single track between passing sidings.

5 I will describe one form of apparatus embodying my invention, and will then point out the novel features thereof in claims.

The accompanying drawing is a diagrammatic view showing one form of apparatus embodying my invention.

10 Referring to the drawing, the reference characters 1 and 1^a designate the track rails of a stretch of railway track over which 15 traffic at times moves in both directions. These rails are divided by insulated joints 2 to form a block A—B, and the rails of this block are further divided by similar insulated joints to form a plurality of track sections 20 A—X, X—Y and Y—B.

25 Located at the point A is a signal S^A which governs traffic moving toward the right through the block A—B, whereas, traffic moving toward the left through this block is governed by a similar signal S^B located at the point B. Each of these signals comprises a proceed lamp G, a caution lamp Y, and a stop lamp R, as well as an auxiliary stop lamp R¹.

30 Located at the point A is a selector relay C^A, and located at the point B is a similar selector relay C^B. These relays are controlled from a distant point through the medium of a despatcher's control line G and 35 selectors F^A and F^B. The control of these relays forms no part of my present invention, and it is sufficient to state that each relay is normally de-energized but that either relay may be energized at the will of the despatcher 40 through the medium of the selectors F.

45 Each end of each track section is provided with a track battery and a track relay. The track batteries are designated E¹, E², etc., whereas, the track relays are designated T¹, T², etc. The battery E³ and the relay T² are associated with the right-hand end of section A—X, the battery E² and relay T³ are associated with the left-hand end of section X—Y, the battery E⁵ and relay T⁴ are associated with the right-hand end of section 50

X—Y, and the battery E⁴ and the relay T⁵ are associated with the left-hand end of section Y—B. It is also understood that the battery E¹ and relay T¹ are associated with the left-hand end of section A—X, whereas, 55 the battery E⁶ and relay T⁶ are associated with the right-hand end of section Y—B.

As shown in the drawing, both of the selector relays C^A and C^B are de-energized. Battery E¹ is connected with section A—B, the path being from the upper terminal of this battery through the back point of contact 3 of relay C^A to track rail 1, and from track rail 1^a through the back point of contact 4 of relay C^A, back contact 11 of a stick relay D^A, and back contact 7 of track relay T¹ to battery E¹. Track relay T² is connected with the rails of section A—X, through the back points of contacts 15 and 16 of track relay T³, so that track relay T² is energized. Battery E² is therefore connected with the rails of section X—Y through the front points of contacts 13 and 14 of track relay T², so that track relay T⁴ is energized, the latter relay being connected with the rails of section X—Y 75 through the back points of contacts 19 and 20 of track relay T⁵. Battery E⁴ is connected with the rails of section Y—B through the front points of contacts 17 and 18 of track relay T⁴. Battery E⁶ is also connected with the rails of section Y—B through the back point of contact 21 of relay C^B, back point of contact 22 of relay C^B, back contact 28 of a stick relay D^B, and back contact 30 of track relay T⁶. Track relays T¹, T³, T⁵ and T⁶ are 80 disconnected from the rails.

85 Lamp R of signal S^A is lighted, the circuit being from terminal B of a suitable source of current, through the back point of contact 8 of relay T¹ and lamp R to terminal O of the same source of current. Lamp R¹ of this signal is also lighted through a circuit which includes the back point of contact 12 of relay D^A. Lamp R of signal S^B is lighted by 90 virtue of a circuit which includes the back point of contact 26 of relay T⁶. Lamp R¹ of signal S^B is also lighted by virtue of a circuit which includes the back point of contact 29 of relay D^B. 95 100

I will first assume that the despatcher desires to allow a train moving toward the left to pass through the block A—B. To do this, he causes selector relay C^B to become energized, thereby disconnecting battery E⁶ from the rails of section Y—B and connecting relay T⁶ with the rails of this section through the front points of contacts 21 and 22 of relay C^B. Track relay T⁶ will then become energized, because track battery E⁴ is connected with the rails of this section. A pick-up circuit for relay D^B will then be closed, which circuit passes from terminal B, through contact 24 of relay T⁶, and the winding of relay D^B to terminal O. The stick circuit for relay D^B will then become closed, which circuit passes from terminal B, through contact 23 of relay C^B, contact 27 of relay D^B, and the winding of relay D^B to terminal O. It follows that relay D^B will remain energized as long as selector relay C^B remains energized, even though track relay T⁶ may open. The circuit for the stop lamp R of signal S^B will then become opened at the back point of contact 25 of relay T⁶, but the auxiliary lamp R¹ of this signal will remain lighted because of a second circuit which includes the front point of the same contact. The proceed lamp G of signal S^B will become lighted by virtue of a circuit which passes from terminal B, through the front point of contact 29 of relay D^B, front point of contact 26 of relay T⁶, and lamp G to terminal O. When the train enters section Y—B, track relay T⁶ will become de-energized, whereupon, the proceed lamp G of signal S^B will be extinguished, and the caution lamp Y of this signal will become lighted because of a circuit including the front point of contact 29 of relay D^B and the back point of contact 26 of relay T⁶. As the train enters section X—Y, it will de-energize track relay T⁴, thereby disconnecting battery E⁴ from the rails of section Y—B, and as the train enters section A—X it will de-energize track relay T², thereby disconnecting battery E² from the rails of section X—Y. It follows that signal S^B will continue to give the caution indication as long as the train occupies any part of block A—B.

If the despatcher desires to permit a train moving toward the right to enter block A—B, he causes selector relay C^A to become energized, thereby connecting track relay T¹ with the rails of section A—X. Track relay T⁵ will then be energized from battery E⁶, track relay T³ will be energized from battery E⁵, and track relay T¹ will be energized from battery E³. It follows that stick relay D^A will become energized by virtue of its pick-up circuit through contact 6 of track relay T¹, and will then remain energized by virtue of its stick circuit through contact 5 of relay C^A and contact 10 of relay D^A. The proceed lamp G of signal S^A will become lighted by

virtue of its circuit through the front point of contact 12 of relay D^A and the front point of contact 9 of relay T¹. When the train enters section A—X, track relay T¹ will open, so that the proceed lamp G will be extinguished, and the caution lamp Y will be lighted by virtue of a circuit through the front point of the contact 12 of relay D^A and the back point of contact 9 of track relay T¹. This condition will continue as the train passes through the block for reasons pointed out hereinbefore in explaining the operation during the movement of a train in the opposite direction.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, a stretch of railway track divided into sections, a track battery and a track relay associated with each end of each section, means for connecting the rails of each end of each two adjoining sections with the associated battery or the associated relay according as the relay for the adjacent end of the adjoining section is energized or de-energized, manually controlled means for selectively connecting the rails at the free end of each end section with the associated battery or the associated relay, and signals for said stretch controlled by the track relays associated with the free ends of the end sections.

2. In combination, a stretch of railway track divided into sections, a track battery and a track relay associated with each end of each section, means for connecting the rails of each end of each two adjoining sections with the associated battery or the associated relay according as the relay for the adjacent end of the adjoining section is energized or de-energized, a manually controlled relay at each end of said stretch, means for connecting the rails at the free end of each end section with the associated battery or the associated track relay according as the associated manually controlled relay is de-energized or energized, and signals for said stretch controlled by the track relays associated with the free ends of the end sections.

3. In combination, a stretch of railway track divided into sections, a track battery and a track relay associated with each end of each section, means for connecting the rails of each end of each two adjoining sections with the associated battery or the associated relay according as the relay for the adjacent end of the adjoining section is energized or de-energized, a manually controlled relay at each end of said stretch, means for connect-

ing the rails at the free end of each end section with the associated battery or the associated track relay according as the associated manually controlled relay is de-energized or energized, a stick relay at each end of said stretch, a pick-up circuit for each stick relay controlled by a front contact of the track relay for the free end of the associated section, a stick circuit for each stick relay controlled by a front contact of the associated manually controlled relay, and signals for said stretch controlled by said stick relays and by the track relays associated with the free ends of said end sections.

4. In combination, a stretch of railway track divided into sections, a track battery and a track relay associated with each end of each section, means for connecting the rails of each end of each two adjoining sections with the associated battery or the associated relay according as the relay for the adjacent end of the adjoining section is energized or de-energized, a manually controlled relay at each end of said stretch, means for connecting the rails at the free end of each end section with the associated battery or the associated track relay according as the associated manually controlled relay is de-energized or energized, a stick relay at each end of said stretch, a pick-up circuit for each stick relay controlled by a front contact of the track relay for the free end of the associated section, a stick circuit for each stick relay controlled by a front contact of the associated manually controlled relay, a signal at each end of said stretch, means for causing each signal to indicate proceed when the associated stick relay and the associated track relay are energized, means for causing each signal to indicate caution when the associated stick relay is energized and the associated track relay is de-energized, and means for causing each signal to indicate stop when the associated stick relay is de-energized.

45 In testimony whereof I affix my signature.
CHARLES A. BROOKS.
